UNITED STATES PATENT OFFICE.

ROBERT G. LARSEN, OF BOSTON, AND WILLIAM S. MORRELL, OF MELROSE, MASSACHUSETTS, ASSIGNORS TO B. F. KEITH THEATRE COMPANY OF BOSTON, A CORPORATION OF MASSACHUSETTS.

SWIMMING-TANK.

1,097,242.

Specification of Letters Patent.

Patented May 19, 1914.

Application filed May 19, 1913. Serial No. 768,458.

To all whom it may concern:

Be it known that we, ROBERT G. LARSEN and WILLIAM S. MORRELL, subjects of Great Britain, and residents, respectively, of Boston, in the county of Suffolk, and Melrose, in the county of Middlesex, and State of Massachusetts, have invented an Improvement in Swimming-Tanks, of which the following is a specification.

- 10 This invention relates to improvements in swimming tanks especially adapted for use in connection with a theatrical stage whereby a performer may dive into the tank and swim about and perform various feats in 15 the water and then disappear and subsequently reappear on the stage in the same or another costume; or may enter the tank unobserved and suddenly appear in the tank in view of the audience.
- 20 The invention consists in the combination with a stage and masking at the side thereof, of a tank arranged beneath the stage floor having an opening at the top adapted to be covered by a removable portion of 25 the stage floor and having a conduit leading from one end of it which extends outward and upward and terminates at or near the stage floor behind the masking at which point the stage floor has another removable 30 portion. The swimmer may dive into the tank from the stage floor in full view of the audience, and swim about and perform various feats in the water and then swim under water into the conduit leading from 35 the tank and emerge from the outlet of said conduit behind the masking, whereupon he may subsequently reappear before the audience with or without a change of costume, or he may enter the conduit behind 40 the masking, and swim under water into the tank into the view of the audience. Before the swimmer dives into the tank and also after he has disappeared and while the audience is waiting for his reappearance, it is desirous 45 to supply something to which the attention of the audience will be directed, and herein, a fountain is provided upon which brilliantly colored rays of light may be projected, the jet or jets of water being projected upward to a considerable height. The nozzle and supply-pipe of said fountain are or may be movably supported whereby they may be moved into and out of position for 50 operation.
- 55 Figure 1 is a longitudinal vertical sec-

tion of a swimming tank embodying this invention in connection with a portion of the theatrical stage. Fig. 2 is a plan view of the swimming tank.

In the embodiment of the invention here shown for the sake of illustration the apparatus is of the knock-down type, whereby it may be assembled and disassembled at will, enabling it to be moved from place to place, but the invention is not limited to this type.

12 represents the floor of a theatrical stage having a removable portion 14, and 15 a masking of any suitable construction which is arranged at the side of the stage.

18 represents the wall of a tank and 20 the bottom thereof, said tank being usually arranged beneath the stage floor. Said tank may be of any size and shape, although here shown as oval, and of sufficient depth 25 to enable a swimmer to swim about freely therein. The wall and bottom of the tank may be composed of pieces of wood, with the exception of one end-portion of the wall, which latter is formed of a metallic plate 30 22, one or more as may be required, having a hole through it near the bottom of ample size to enable a swimmer to pass through it, and said parts are secured together by metallic straps or bands of any suitable construction and in any suitable manner. At the hole in the plate 22 a conduit 26 is connected in a water-tight manner, which conduit is usually of cylindrical form. This extends outward and upward and terminates 35 at the stage floor behind the masking 16, at which point a portion of the stage floor 17 is made removable. Said conduit may be composed of pipe-sections secured together. As the conduit is usually quite long and 40 heavy it is necessary to support it, and, as here shown, it has outstanding lugs 27, to receive bolts 28, passing through cross-bars 29, which are stationarily supported.

45 The removable portions 14 and 17 of the stage floor having been removed, the top of the tank and the end of the conduit are exposed, then the swimmer, in full view of the audience, will dive into the tank and subsequently swim under water into the conduit 50 and emerge therefrom back of the masking, and subsequently reappear on the stage, or may enter the conduit and swim under water 55 into the tank and emerge therefrom in view of the audience.

110

The fountain which is employed comprises a nozzle 30, from which jets of water issue, and a supply-pipe 32 connected to said nozzle. Said pipe extends through a stuffing-box arranged in the wall of the tank, and is 5 slidably supported in said box, so that the nozzle may be moved to a position at the end of the tank, as represented by dotted lines Fig. 2. The supply-pipe 32 may have 10 an upwardly extended portion at its inner end and a downwardly extended portion at its outer end, and said pipe may be given a quarter turn to submerge the nozzle, if desired, the position of the nozzle being indicated 15 by the position of the angularly formed portion at the outer end of the pipe. The supply-pipe usually will be connected at its outer end with a flexible hose 34, which admits of a sliding and also a rotary movement thereof.

We claim:—

1. The combination with a theatrical stage having a masking and a swimming-tank in

connection with the stage arranged in front of the auditorium, and having a large conduit leading from it, which terminates behind the masking, through which a swimmer may pass, substantially as described. 25

2. The combination with a theatrical stage 30 having a masking and having portions of its floor removable, respectively, in front of the auditorium and behind the masking, and a swimming-tank arranged beneath the stage floor in front of the auditorium having a large conduit leading from it which extends 35 outward and upward and terminates at the stage floor behind the masking, substantially as described.

In testimony whereof, we have signed our names to this specification in the presence of 40 two subscribing witnesses.

ROBERT G. LARSEN.
WILLIAM S. MORRELL.
